UNITED STATES PATENT OFFICE

168,884

CHINA STAND

Albert Chicorel, Detroit, Mich.

Application April 18, 1951, Serial No. 14,883

Term of patent 14 years

(Cl. D80—9)

To all whom it may concern:

Be it known that I, Albert Chicorel, a citizen of the United States of America, residing at Detroit, in the county of Wayne and State of Michigan, have invented a new, original, and ornamental Design for a China Stand, of which the following is a specification, reference being had to the drawing, forming a part thereof.

Fig. 1 is a top view of a china stand embodying my new design.

Fig. 2 is a front elevation thereof.

Fig. 3 is a sectional view along the lines 3—3 in Fig. 2.

Fig. 4 is a sectional view along the lines 4—4 in Fig. 2.

I claim:

The ornamental design for a china stand, substantially as shown.

ALBERT CHICOREL.
